UNITED STATES PATENT OFFICE.

THEODORE E. LUTZ, OF GALION, OHIO.

ADJUSTABLE CRANK ATTACHMENT.

971,764.

Specification of Letters Patent.

Patented Oct. 4, 1910.

Application filed November 16, 1908. Serial No. 462,887.

To all whom it may concern:

Be it known that I, THEODORE E. LUTZ, a citizen of the United States, residing at Galion, in the county of Crawford and State of Ohio, have invented a new and useful Adjustable Crank Attachment, of which the following is a specification.

The invention relates to an adjustable crank attachment.

The object of the present invention is to provide a simple, inexpensive and efficient crank attachment, designed particularly for use in connection with the operating mechanism of railways, signals, etc., but capable of being employed in any operating mechanism where it is desired to transmit the throw or motion of an actuating lever and change the direction of the transmitted motion, and adapted to increase and decrease the transmitted motion and to take up lost motion and also to enable the direction of the transmitted motion to be changed.

A further object of the invention is to provide an adjustable crank attachment, adapted to be substituted for an ordinary bell crank lever and capable of enabling the precise throw or movement of an operating or actuating lever to be accurately maintained at all times.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:—Figure 1 is a plan view of an adjustable crank attachment, constructed in accordance with this invention. Fig. 2 is a side elevation of the same. Figs. 3 and 4 are detail views of the oscillatory vibratory member. Fig. 5 is a vertical sectional view on the line 5—5 of Fig. 1. Fig. 6 is a plan view of a crank attachment, illustrating a modification of the invention, the oscillatory member operating within one of the arms of the bell crank lever.

Like numerals of reference designate corresponding parts in all the figures of the drawings.

1 designates a stand or bracket consisting of a base plate 2 and an upwardly ext-

ing portion 3, braced by a rib or flange 4 and provided with a horizontal overhanging arm 5, arranged in spaced relation with the base plate to provide an intervening opening 6 for a bell crank lever 6. The base plate is provided beneath the arm with a circular boss 7, forming a seat or bearing for the bell crank lever, which is pivoted in the space or opening 8 by a pin 9, piercing the top and having its lower end fitted into a socket 10 of the base plate. The pin or pivot 9 is retained in place by a split key 11, and it is provided at its upper end or head with an annular groove 12, adapted to receive a suitable tool or instrument to enable the pivot to be readily removed from the stand. The key 11, which is arranged horizontally, pierces the upper arm and passes through an opening 13 of the pivot or pin 9. The base plate is provided with openings 14^a for the reception of fastening devices for securing it to a suitable support. While the bell crank lever is illustrated in a horizontal position, the adjustable crank attachment is capable of operating in any position.

The bell crank lever, which is shown L-shaped in the accompanying drawings, may be of any other form to provide the desired number of arms. The arm 14 receives and extends into an oscillatory vibratory member 15, tapered inwardly, as clearly illustrated in Figs. 1 and 4 of the drawings, and slotted edgewise to form a casing and to provide spaced upper and lower plates or portions, which are connected at the outer end, but which may also be connected at the sides if desired. The arm 14 is arranged in the intervening spaces 16 between the upper and lower plates or portions of the member 15, which is pivoted to the arm 14 by means of a vertical pivot 17, located beyond the pivot of the bell crank lever, but it will be readily apparent that the pivot of the bell crank lever may also be utilized for pivotally connecting the member 15 with the bell crank lever. As this change is obvious, illustration thereof is deemed unnecessary. The pivot 17, which pierces the bell crank lever and the upper and lower plates or portions of the member 15, is retained in place by a split key 17^a, and washers are also arranged at the top and bottom of the member 15 and interposed between the same and the head of the pivot 17 and the key 17^a. The vibratory member 15 is capable of a limited pivotal movement independent

of the arm of the lever, and this movement is controlled by opposite stops located at the side edges of the member 15 and consisting of set screws 18, mounted in threaded 5 openings 19 of connecting walls or flanges 20 and movable inwardly and outwardly to vary the distance between their inner ends 21, which are rounded as shown. The set screws are secured in their adjustment by 10 lock nuts 22, engaging bosses or enlargements 23 of the flanges or walls 20, as clearly illustrated in Fig. 1 of the drawings. The adjusting screws are adapted to increase or decrease the independent movement of 15 the member 15, and they are also capable of holding or locking the member 15 rigid with the arm 14 of the bell crank lever.

The device through the adjustment of the screws is adapted to maintain the precise 20 throw of an operating or actuating lever, so that a movement of the same to and from a given point will produce the desired movement of the mechanism actuated by the lever, and in event of an excessive movement of an actuating lever, the device will 25 take care of the success of the movement and only the desired amount of movement will be transmitted to the mechanism to be operated. The adjustable stops, when employed for locking the member 15 and the 30 arm 14 of the bell crank lever rigid with each other, will permit a relative adjustment of the parts for changing the angle or direction of the transmitted motion. The member 35 15 is provided at its outer end with an ear 24, which by means of the said adjustment, can be secured either at right angles to the arm 25 of the bell crank lever or at an obtuse or acute angle to the same, and the 40 member 15 may be varied in width to secure the desired adjustment of the parts. The controlling action of the set screws in limiting the relative movement of the parts will enable lost motion and wear and changes 45 incident to the action of the elements to be taken up or collected. The rod 26, which is pivoted to the ear 24 by a bolt or pin 27, may be connected with the actuating lever, and the arm 25 of the bell crank lever may 50 be connected through the rod 28 with the device or part to be actuated, but the attachment may be reversed and if desired each arm of the bell crank lever may be equipped with an adjustable member. The connecting 55 rods 26 and 28 are angularly related, and the adjustable crank attachment constitutes means for transmitting motion from one rod to the other.

In Fig. 6 is illustrated a modification of 60 the invention, in which the bell crank lever 29 has one of its arms slotted edgewise and receiving a vibratory member 30. The arm 31 of the bell crank lever is in the form of a casing and is constructed similar to the 65 vibratory member 15, and it is provided at

opposite sides with threaded openings 32 for the reception of set screws 33, which form stops for limiting the independent movement of the vibratory member 30. The set screws are secured in their adjustment 70 by lock nuts 34, and the vibratory member 30 is pivoted at its inner end to the bell crank lever by a pin 35, provided at its inner end with a head and secured at its lower end by a key 36. Washers are also preferably 75 arranged on the pin 35 at the top and bottom of the arm 31 of the bell crank lever. The outer end of the vibratory member 30 extends beyond the casing or housing formed by the arm 31 and provides an ear for the 80 attachment of a rod 37. The bell crank lever 29 is connected with a rod 38. Rods like those illustrated in Fig. 1 are designed to be connected with or form a portion of any rod or pipe connection, or similar connecting means between the actuating lever and the device or part to be moved by the same.

Having thus fully described my invention, what I claim as new and desire to secure by 90 Letters Patent, is:—

1. In operating mechanism for railways, signals, etc., the combination with a pair of angularly related connecting rods, of an adjustable crank attachment including a 95 support, a lever pivoted at an intermediate point to the support and having one of its arms pivotally connected with one of the said rods, an oscillatory member pivoted to the other arm of the lever beyond the pivot thereof, one of the parts being tapered and receiving and forming a casing in which the other part has a limited independent movement, means for pivotally connecting the said member to the other connecting rod, and adjustable means located at opposite sides of the casing for limiting and varying the independent movement of the lever and the oscillatory member. 100

2. In operating mechanism for railways, signals, etc., the combination with a pair of angularly related connecting rods, of an adjustable crank attachment including a lever having one of its arms pivotally connected 105 with one of the said rods, a vibratory member pivotally mounted on and carried by the other arm of the lever and provided at its inner portion with an opening through which the lever extends, said member being pivoted to the other connecting rod and having a limited movement independent of the lever, and adjustable stops mounted on the member at opposite sides of the lever for engaging the same to vary the independent 110 movement of the parts. 115

3. In operating mechanism for railways, signals, etc., the combination with a pair of angularly related connecting rods, of an adjustable crank attachment including a lever having one of its arms pivotally connected 120 125 130

with one of the said rods, an inwardly tapered vibratory member consisting of a casting and having an opening at its inner portion through which the other arm of the lever extends, said member being pivoted at its inner end to the lever and having a cold outer end provided with an ear pivotally connected with the other rod, and adjustable stops mounted on the member at 10 opposite sides of the same for varying the

independent movement of the lever and the member.

In testimony, that I claim the foregoing as my own, I have hereto affixed my signature in the presence of two witnesses.

THEODORE E. LUTZ.
